[57] CLAIM

The ornamental design for furniture top, as shown and described.

DESCRIPTION

FIG. 1 is a perspective view of a furniture top showing my new design;

FIG. 2 is a front elevational view; and

FIG. 3 is a right side elevational view, the left side being a mirror image thereof.

The broken lines are for illustrative purposes only. No illustration of the rear and bottom are shown, as they are plain and unadorned.
